UNITED STATES PATENT OFFICE

DEAN M. SOLENBERGER, OF CLEVELAND, OHIO, ASSIGNOR TO THE SIMPLEX PISTON RING CO. OF AMERICA, INC., OF CLEVELAND, OHIO, A CORPORATION OF OHIO

APPARATUS FOR SLOTTING PISTON RINGS

Application filed June 27, 1927. Serial No. 201,836.

The invention relates to apparatus for slotting of piston rings of that type in which axial resiliency is imparted to the ring by parallel series of overlapping slots. Such rings are formed usually from cast iron and are originally of a width greater than that of the groove in which they have been inserted. The overlapping slots form flexible intermediate sections which permit of compressing the ring axially to fit the ring groove but it is of the utmost importance that the resilient pressure against the sides of the groove should be accurately determined. It is equally important that the resilient axial pressure should be substantially equal in all portions of the ring and that no portion should be unduly weakened so as to endanger breakage.

To fulfill the conditions just described, it is necessary that the slotting of the rings should be very accurately performed and that both the width and the length of the flexible sections should be accurately predetermined. With this object in view the invention consists in the peculiar construction of means for holding and slotting the rings as hereinafter set forth.

In the drawings:

Figure 1 is a plan view showing the saw arbor and the ring holding jig with sections of the latter detached for the removal of the work.

Figure 2 is a side elevation parallel in section showing the saw in engagement with the work.

Figure 3 is a longitudinal section through the jig.

Fig. 4 is an elevation of one of the ring holders.

Figure 5 is a greatly enlarged cross section through a portion of the jig showing the ring held therein in position for slotting.

Figure 6 is a side elevation of one of the ring supports.

Figure 7 is a developed side elevation of the slotted ring.

As shown in Figure 7 the completed ring A is provided with parallel circumferential series of slots B, B', C, C' which extend completely around the circumference leaving

short uncut portions D between adjacent slots of each series. The ring is trans-split and the ends on opposite sides of the split preferably overlap as shown at E and E'. These end portions must also be axially compressible which is preferably accomplished by extending one of the slots C² across the split and the portions of the ring on opposite sides thereof. The series of slots B, B', C, C' are staggered with respect to each other which forms intermediate said slots a series of flexible bars F connected at one end by the uncut portion D to one side of the ring and at the opposite end by a similar uncut portion D to the opposite side of the ring. The bars F are resiliently flexible and the axial pressure developed against the sides of the ring groove is determined by the cross section of said bars in proportion to the length thereof. Thus it is important that both length and thickness of these bars should be accurately predetermined.

The slotting of the rings is accomplished by circular saws or mills which are necessarily of small gauge and consequently are very flexible. Thus using such saws without guiding means it would be impossible to slot the rings with any degree of accuracy or uniformity. Another difficulty is due to the small cross section of the ring and the flexibility of the portions adjacent to the slots. Still another difficulty is due to the fact that the ring is trans-split and therefore is radially flexible.

In view of the conditions just described I have devised a construction of jig which will hold the ring accurately positioned and against either axial or radial displacement and which will also accurately guide the saws while operating upon the ring and in a predetermined plane thereof. This jig may be mounted upon any suitable construction of rotary indexing head (not shown) and on any suitable tool such as a milling machine for moving such head relative to the saw arbor during the performance of the work, the specific construction being as follows:

In the drawings I have merely shown an arbor 1 on which the saws are mounted and in dotted lines the face plate 2 of the rotary

indexing head (not shown). The jig comprises a head member 3 which is concentrically positioned upon the face plate 2 and clamped thereto by suitable means such as the shank or bolt 4. This shank 4 may be formed integral with an arbor 5 having a tapered portion 6 seated in a correspondingly tapered recess in the head 3. On this arbor are sleeves one or more disk members 7 held from rotation by the key or spline 8 and in cooperation with the head 3 forming the ring holders. The members 7 are accurately spaced from the head 3 and from each other by spacer rings 9 arranged adjacent to the center or hub portions thereof. 10 is a threaded outer end portion of the arbor 5 and 11 is a winged nut or other means engaging said threaded portion for clamping the whole series of members 7 and 3.

20 For holding the rings concentric with the axis of the jig and radially compressed to the working diameter each of the members 3 and 7 is provided with a peripheral flange 12 forming a seat for the outer cylindrical face 25 of the ring. These flanges 12 on adjacent members are spaced from each other by a distance equal to the gauge of the saw plus a slight addition for working clearance. The outer faces of the flanges are beveled off as 30 shown at 13 leaving only a narrow portion 14 for bearing against the saw. The saws 15 are mounted upon the arbor 1 and are suitably spaced to register with the guide slots between the flanges 12 of the successive members 3 and 7. Thus when the jig is properly 35 indexed and is moved laterally with respect to the arbor 1 the saws 15 will be guided into engagement with the rings which are between the successive members of the series.

40 To permit of using the same saw guides for forming the parallel slots in different planes of the ring the space between the members 3 and 7 as determined by the spacers 9 is greater than the width of the ring so that the latter may be offset to one side of such space as shown in Figure 5. The opposite side of the ring is positioned by a spacer ring 16 which also has an annular shoulder 17 for fitting against the inner cylindrical face of the piston ring and holding the same from displacement under the radial thrust of the saw. The spacer 16 is split or cut away at 18 to permit of a slight radial contraction during engagement of the shoulder 17 with the piston 50 ring and the radial depth of the spacer ring is sufficient to give the desired degree of rigidity in resisting radial thrust of the saws.

With the construction as described, in operation an unslotted piston ring is first engaged with the flange 12 of the member 3, the ring being held outward against such flange by its own radial resiliency. The spacer ring 16 may then be engaged with the outer portion of the ring, the shoulder 17 extending inside of the ring to a point adja-

cent to the plane of the saw guide. The member 7 is then moved on the arbor 5 up against the spacer ring 9, the flange 12 overlapping the spacer ring 16 and the projecting portion of the piston ring. The second piston ring is then engaged with the flange 12 on the opposite side of the member 7 and the operation repeated until the desired number of rings are engaged with the jig. The nut 11 is then tightened to clamp the parts in this position thereby holding all of the piston rings from displacement in any direction and without exerting pressure on them axially.

In order that the slots may be properly positioned with respect to the joint in the ring, a stop is arranged for locating each joint in a predetermined position in the jig. This stop may be formed by a member 19 preferably a piece of sheet metal placed in a saw kerf in the flange 12. The stop projects far enough into the recess for the ring so as to enter the narrow space between the ring ends thus holding said ring from circumferential displacement. The sawing or slotting is effected by moving the jig arbor towards the saw arbor which causes each of the saws to enter the space between the guide faces 14 to cut completely through the ring. The length of the slot is determined by the diameter of the saw and the amount of radial inward movement. Also these two factors are preferably such that the ends of the slots will be substantially square or in other words, that the edge of the saw when completing the slot will extend substantially radially with respect to the ring. After the cutting of each slot the index head is adjusted to position the jig for the cutting of the next adjacent slot and so on until the whole series in the same plane is completed. The jig is then unclamped, the rings removed and the spacer rings 16 are placed on the opposite side of each piston ring. This when the jig is again assembled will position each of the piston rings on the opposite side of the recess in which it is held which will space the second series of slots from the plane of the first series. The amount of this spacing and the consequent width of the intermediate flexible bars of the rings is determined by the ratio of the width of the ring to the width of the recess in which said ring and spacer 16 are located. Thus, in originally designing the jig any desired spacing of the slots may be arranged for.

It will be noted that in this sawing operation there is no reversal of the rings with respect to the saws but that the parallel slots are formed by a lateral shifting of the rings due to the placing of the spacer ring first on one side and then on the other thereof. Thus if there is any tendency of the saw to lead in one direction it will take the same direction in cutting each of the parallel slots so as to maintain these slots parallel. It will also be noted that the portion of the ring which is under

the direct thrust of the saw will be supported against radially inward movement by the shoulder 17 on the spacer ring 16. This will prevent any displacement of the piston ring during the sawing operation. During the sawing operation there is no axial pressure against the ring as the clamping pressure is taken by the spacer rings 9. This prevents any deformation of the ring after the cutting of the first series of slots and the fact that the saw pressure is all radial prevents lateral displacement by the saw.

What I claim as my invention is:

1. A jig for holding a piston ring comprising a pair of complementary axially adjustable members each having a cylindrical flange against which the outer cylindrical face of the ring bears, said flanges together constituting a guide for a cutter, said jig and cutter being relatively movable for effecting engagement of the cutter with the ring and means for holding the ring from inward displacement under the thrust of the cutter.

2. A jig for holding a piston ring comprising a pair of complementary axially adjustable members each having a cylindrical flange against which the outer cylindrical face of the ring bears, said flanges together constituting a guide for a cutter, said jig and cutter being relatively movable for effecting engagement of the cutter with the ring, means for holding the ring within said flanges in a plurality of laterally offset positions with respect to the plane of the cutter and for also holding the ring from inward displacement under the thrust of the cutter in each of said positions.

3. A jig for holding a piston ring comprising a pair of complementary members each having a cylindrical flange forming a bearing for the outer cylindrical surface of the piston ring, means for holding said members spaced and forming a recess beneath said flanges of greater width than the width of the ring and with the flanges spaced from each other to form a guide for a cutter and a spacer ring complementary to said piston ring to fill the space between said members and to hold said ring laterally offset with respect to the cutter guide, said jig and cutter being relatively movable for effecting engagement of the cutter with the ring.

4. A jig for holding a piston ring comprising a pair of complementary members each having a cylindrical flange forming a bearing for the outer cylindrical surface of the piston ring, means for holding said members spaced and forming a recess beneath said flanges of greater width than the width of the ring and with the flanges spaced from each other to form a guide for a cutter, said jig and cutter being relatively movable for effecting engagement of the cutter with the ring and a spacer ring complementary to said piston ring to fill the space between said

members and to hold said ring laterally offset with respect to the cutter guide, said spacer ring having a shouldered bearing for fitting within the piston ring and holding the same from radial inward displacement 7c

5. A jig for holding a piston ring comprising a pair of complementary members each having a cylindrical flange forming a bearing for the outer cylindrical surface of the piston ring, means for holding said members spaced and forming a recess beneath said flanges of greater width than the width of the ring and with the flanges spaced from each other to form a guide for a cutter, said jig and cutter being relatively movable for effecting engagement of the cutter with the ring and a spacer ring complementary to said piston ring and adapted to be alternately placed on and engaged with opposite sides 80 thereof to fill the space between said members and to hold the ring offset to one side or the other with respect to the plane of the cutter, said spacer ring having a shoulder for fitting within the piston ring and holding the same against the radial inward thrust of the cutter.

6. A jig for holding a piston ring comprising a pair of complementary members each having a cylindrical flange forming a bearing for the outer cylindrical surface of the piston ring, means for holding said members spaced and forming a recess beneath said flanges of greater width than the width of the ring and with the flanges spaced from each other to form a guide for a cutter, said jig and cutter being relatively movable for effecting engagement of the cutter with the ring and a spacer ring complementary to said piston ring and adapted to be alternately placed on and engaged with opposite sides 95 thereof to fill the space between said members, said ring having a shoulder for fitting within said piston ring to hold the same from radial inward displacement under the thrust of the cutter and said spacer ring being split to permit of a slight radial contraction during the engagement with the piston ring.

7. A jig for holding a piston ring comprising a pair of complementary axially adjustable members each having a cylindrical flange against which the outer cylindrical face of the ring bears, said flanges together constituting a guide for a cutter, said jig and cutter being relatively movable for effecting engagement of the cutter with the ring and means for holding the ring from radial inward displacement under the thrust of the cutter, and a stop engaging the trans-split in the ring for holding the same from circumferential displacement in said jig.

8. A jig for holding a piston ring comprising a pair of complementary members each having a cylindrical flange for bearing 130

against the outer face of the piston ring and together constituting a guide for a cutter, said jig and cutter being relatively movable for effecting engagement of the cutter with the ring, and means for holding said ring from inward displacement under the radial thrust of said cutter.

9. A jig for holding a series of piston rings adapted to be engaged by a series of cutters, said jig comprising a member having a cylindrical flange for fitting against the outer face of the piston ring, the outer edge of said flange forming a guide for one of said cutters, a member having a complementary oppositely arranged flange, one or more intermediate members provided with double oppositely arranged flanges, spacers between the several members for holding the cutter guiding faces of adjacent flanges spaced from each other to provide running clearance for the cutters and also forming recesses beneath said flanges of greater width than the width of the piston rings, spacer rings complementary to said piston rings and adapted to be alternatively placed on and engaged with the opposite sides thereof to fill the space of said recesses and to offset the piston rings on one side or the other of the plane of the cutter, said spacer ring having a shoulder for fitting within the piston ring and for holding the latter from radial inward movement under the thrust of the cutter and means for clamping all of said members in fixed relation and so as to register the respective cutter guides with the corresponding cutters.

10. A jig for supporting a piston ring comprising complementary members, each having a lateral annular extension fitting against the outer cylindrical face of the ring, said extensions having their outer edges arranged in opposed spaced relation and together constituting a guide for a tool to be passed therebetween.

11. A jig for supporting a piston ring comprising complementary members, each having a laterally extending annular flange bearing against the outer cylindrical face of the ring, said flanges having their outer edges arranged in opposed spaced relation and together constituting a guide for a tool to be passed therebetween.

12. A jig for supporting a piston ring comprising complementary members, each having a laterally extending annular flange bearing against the outer cylindrical face of the ring, said flanges having their outer edges arranged in opposed spaced relation and together constituting a guide for a tool to be passed therebetween, said jig and tool being relatively movable for effecting engagement of the tool with the ring, and means for preventing inward displacement of the ring under the thrust of the tool.

65 In testimony whereof I affix my signature.
DEAN M. SOLENBERGER.
